CLAIM

The ornamental design for an excavator part, as shown and described.

DESCRIPTION

The patent or application file contains at least one drawing executed in color. Copies of this patent or patent application publication with color drawing(s) will be provided by the Office upon request and payment of the necessary fee.

FIG. 1.1 is a left side perspective view of an excavator part showing our new design.

FIG. 1.2 is a reduced left front perspective view of an excavator part shown in environmental use.

FIG. 1.3 is an enlarged right-side view of an excavator part. FIG. 1.4 is a reduced right-side view of an excavator part shown in environmental use.

FIG. 1.5 is an enlarged left-side view of an excavator part. FIG. 1.6 is a front view of an excavator part.

The very lightly shaded gray color and black & white portions of the claim consisting of: The front bucket and arm assembly, the rear swing arm and bucket assembly, the wheels, the body, cab, and undercarriage form no part of the claimed design. The shadow cast at the bottom of reproductions 1.2 and 1.4 forms no part of the claimed design.

The areas of the claim consisting of the hood and grill excavator portion shown in full color with black and white areas shown in full values represent the claimed design. It is understood that there is a slight color variation that occurs where the unclaimed areas overlap the claimed portion of the design. This variation simply shows unclaimed portions in an environmental setting and does not alter the claimed areas.
